UNITED STATES PATENT OFFICE.

OMI GRANT PHILLIPS, OF PORTLAND, OREGON.

ROADWAY SANDER.

Application filed December 1, 1923. Serial No. 678,055.

To all whom it may concern:

Be it known that I, OMI GRANT PHILLIPS, a citizen of the United States, residing at Portland, in the county of Multnomah and 5 State of Oregon, have invented certain new and useful Improvements in Roadway Sanders; and I do declare the following to be a full, clear, and exact description of the invention, such as will enable others 10 skilled in the art to which it appertains to make and use the same.

My invention relates to improvements in roadway sanders for numerous kinds of vehicles, and the present disclosure is de- 15 signed primarily for use upon motor vehicles, whether passenger cars, commercial cars or heavy trucks.

It is one of the main objects of the invention, to provide a sanding device which 20 may be operatively connected with the brakes of the vehicle by which it is carried, so that sand will be automatically discharged in front of the braking wheels, as soon as the brakes are applied thereto, pro- 25 vision being made however, whereby the discharge of sand may be prevented when its use is not necessary.

In most instances, the sanding device is 30 operated only to a limited extent, by application of the brakes, and a further aim is to provide a separate control means whereby the sander may be more effectively operated if desired.

Yet another object of the invention is 35 to provide a manual control means having two functions, one function being to hold the sander against operation with the brake mechanism if desired, while the other function is to operate the sander more effective- 40 ly than it can be operated by the brakes, the more effective operation being in most instances controlled, by effecting greater opening of a sand discharge valve.

Yet another object of the invention is to 45 provide means for utilizing the exhaust gases from an automobile engine to heat the sand in a sand container to keep the sand in a dry condition and prevent packing and consequent clogging of the outlet.

With the foregoing in view, the invention 50 resides in the novel subject matter herein- after described and claimed, the description being supplemented by the accompanying drawing.

Figure 1 is an elevational view, partly in 55 section, illustrating my invention, the sand-

ing means being held against operation by a manually adjustable control rod.

Figure 2 is a view similar to Fig. 1, but showing the control rod moved to another 60 position, permitting limited operation of the sander under the influence of the brake mechanism.

Figure 3 is a view similar to Figs. 1 and 2, but illustrating the control rod moved to 65 still another position, for the purpose of permitting greater discharge of sand.

Figure 4 is an elevation partly in section, illustrating the manner in which the sand 70 container is heated by the exhaust gases from the engine.

In the drawing above briefly described, sanding means have been shown, supported by transverse bars 1 which are in turn se- 75 cured to a vehicle frame. This sanding means, in the present disclosure, includes a sand container or hopper 2 having an outlet neck 3 and a rotary slide or control valve 4 for said neck. Preferably, two of the con- 80 tainers are provided on the same machine, with their outlets in position to discharge sand immediately in front of the rear 85 wheels. On machines using four wheel brakes, it is obvious that provision may be made for discharging the sand in front of all four wheels.

The valve 4 is shown provided with a controlling member, preferably in the form of an upstanding crank arm 5 which may be connected by a suitable spring device 6 with 90 a portion of the vehicle frame as indicated at 7, so that the valve 4 is normally held closed, as shown in Fig. 1. An operating rod 8 has been illustrated, passing slidably through a guide 9 carried by the arm 5, 95 said rod having an elastic connection with the arm, which connection is preferably established by means of a coiled compression spring 10 bearing at one end against the arm 5 and at its other end against a nut 100 or other shoulder 11 on said rod. The front end of the rod 8 is adapted for connection with the brake mechanism of the automobile or other vehicle upon which the sander is used, and for sake of illustration, I have 105 shown said rod connected directly with a foot brake pedal 12, so that when certain parts hereinafter described, are properly set, application of the brakes will open the valve 4 to discharge a quantity of sand, as il- 110 lustrated in Fig. 2. Means are provided however to hold the sander against opera-

tion when the brakes are not applied.

tion, when its use is not desired, this means being preferably of the construction described below.

A horizontal rod 13 has been shown, 5 pivoted to the upper end of the arm 5 at one of its ends, as indicated at 14, the other end of said rod having a guide eye 15. Passing slidably through this guide eye, is a control rod 16 whose rear end is formed 10 with a guide eye 17 through which the rear portion of the rod 13 passes slidably. The front end of the rod 16 is adapted to be connected with any suitable hand control, such as the lever 18. When the use of the 15 sander is not required, the rod 16 is moved rearwardly until its guide 17 strikes the upper end of the arm 4 and thus prevents the latter from moving forwardly when the brakes are applied. The application of the 20 brakes is not interfered with however, as the elastic connection 10 will yield and permit said brakes to operate. When the rod 16 is moved forwardly to the position disclosed in Fig. 2, it will be seen that operation 25 of the brake mechanism to apply the brakes to the machine, will swing the arm 5 forwardly to a limited extent, thereby partially opening the valve 4 and allowing some discharge of sand. If the amount of sand 30 then discharged is insufficient, the rod 16 may be pulled still further forward, until its guide 17 strikes a stop 19 on the rod 13, whereupon further forward movement of said rod 16, will pull the valve arm to a 35 greater extent, thereby permitting greater opening of the valve, as will be clear by reference to Fig. 3.

In order that the sand in the container 2 may be kept dry, I prefer to provide the 40 lower portion of said container with a heating chamber 20 into which exhaust gases from the engine are discharged. In the present disclosure, a pipe 21 is shown leading from the engine muffler 22 to conduct 45 the gases to the chamber 20, from which they may escape, for instance through an opening 23.

It will be seen from the foregoing that the invention is rather simple and inexpensive, yet will be highly efficient and desirable, regardless of the form of vehicle upon which it is used. However, attention may be directed to the fact that while the novel 50 operating means for the sander is preferably used in connection with a sander having heating means, said operating means might be used in connection with other

forms of sanders. Similarly, the heating feature of the sander is applicable to numerous types of sanding mechanisms, regardless of the exact manner in which they are operated.

Excellent results are obtainable from the details disclosed and they are therefore preferably followed, but within the scope of 60 the invention as claimed, numerous changes may be made. On touring cars, the sand containers are preferably in the back of the front seat, hidden from view, with convenient openings for filling.

I claim:

1. A roadway sander comprising sanding means adapted to be carried by a brake equipped vehicle, elastic operating means for said sanding means adapted for connection with the brake mechanism of the vehicle to operate the sanding means when the brakes are applied, and means engaged with the sanding means for holding the latter against operation when the brake mechanism is actuated.

2. A roadway sander comprising sanding means adapted to be carried by a brake equipped vehicle, elastic operating means for said sanding means adapted for connection with the brake mechanism of the vehicle to operate the sanding means when the brakes are applied, and manually controlled means associated with said operating means and engaged with said sanding means for holding the latter against operation when the brakes are applied and for actuating said sanding means independently of the brake mechanism when desired.

3. A roadway sander comprising sanding means adapted to be carried by a brake-equipped vehicle, an operating rod having an elastic connection with a movable controlling part of said sanding means, said rod being adapted for connection with the 100 brake operating mechanism of the vehicle, a second rod parallel with the first named rod and having a guide slidably on said first named rod and capable of abutting the above-mentioned controlling part of said sanding means to prevent operation thereof, and a stop on said first named rod adapted to be struck by said guide to move said first named rod when the other rod is longitudinally moved.

In testimony whereof I have hereunto affixed my signature.

OMI GRANT PHILLIPS.
